UNITED STATES PATENT OFFICE.

WILLIAM BURKE AND WILLIAM HENRY THOMPSON, OF EAST STROUDSBURG,
PENNSYLVANIA.

MACHINE FOR APPLYING WOOD PULP OR FIBER TO BOTTLES, &c.

SPECIFICATION forming part of Letters Patent No. 660,093, dated October 23, 1900.

Application filed March 17, 1899. Serial No. 709,416. (No model.)

To all whom it may concern:

Be it known that we, WILLIAM BURKE and WILLIAM HENRY THOMPSON, citizens of the United States, residing at East Stroudsburg, 5 Monroe county, State of Pennsylvania, have invented certain new and useful Improvements in Machines for Applying Wood Pulp or Fiber to Bottles, Demijohns, and the Like, of which the following is a specification.

10 Our invention consists in the features of structure and combination of parts hereinafter fully set forth, and particularly pointed out in the claims.

In the accompanying drawings, Figure 1 is 15 a central vertical section of the machine adapted for making bottles. Fig. 2 is a plan view of the chuck and attached parts. Fig. 3 is a bottom plan view of the chuck-operating cam-ring. Fig. 4 is a side elevation of 20 the saucer of the bottle-machine. Fig. 5 is a face view of one of the chuck-jaws.

A saucer 6 is supported upon the posts 1'. This saucer is of concave form and is adapted to fit the upper part or shoulder of the 25 body of the bottle, so that when the bottle is resting in the saucer its neck will depend through the central opening thereof into line with the jaws 4, the said jaws being of concave form on their inner faces and inclining 30 toward each other downwardly to conform to the taper shape of the bottle-neck. The jaws are carried by the stems 7, moving in the guides 8 upon the bed-plate 1, and they are operated toward and from each other by the cam 35 9 on the under side of the cam-ring 10, which is operated by handles 11. The cam-ribs 9 extend downwardly between projections 12 on the upper faces of the stems 7. We have shown in the drawings four chuck-jaws, and 40 consequently employ four cam-ribs, which, as shown in Fig. 3, are eccentric to the center of the cam-ring. The inner edge of the cam-ring bears against the posts 1' and is held in place by the pieces 13, secured to the posts.

45 When the cam-ring is turned in the direction of the arrow, Fig. 2, the chuck-jaws are forced toward each other and they press the pulp or fiber which has been placed on the bottle firmly thereon and mold it thereto. 50 They have a series of perforations extending from the inner to the rear faces, through which

the moisture from the pulp may pass. The saucer is likewise perforated, so that the moisture from the pulp which is expressed when the bottle is forced downward will be free to 55 pass from the saucer. The upper ends of the jaws are curved to form practically continuations of the saucer and to accurately fit the bottle. The head of the bottle projects below the jaws, as shown in Fig. 1. 60

Referring to Fig. 2, it will be seen that each jaw has a lip or extension 14', which projects in rear of a corresponding inclined face on the adjacent jaw, and by this arrangement the inner surface of the chuck is kept continuous for all positions of the jaws, as the inclined face of each projection affords a bearing or a contact-surface for the edge of the adjacent jaw in all the positions thereof. 65

We do not wish to limit ourselves to the 70 number of chuck-jaws, as any number may be used.

The pulp is placed on the bottle by hand while it is in a soft condition, and the jaws then press it into shape. 75

We claim as our invention—

1. In combination in a machine for applying wood pulp or fiber to bottles and the like, a series of chuck-jaws, with means for operating them and the saucer for supporting the 80 bottle, said saucer being arranged above the chuck-jaws, substantially as described.

2. In combination in a machine for applying wood-pulp to bottles, a series of chuck-jaws having perforations, means for operating the jaws, a saucer or support for the bottle above the jaws, said saucer also having perforations, substantially as described. 85

3. In combination, the base-plate having the guides, the jaws having the stems moving 90 in said guides, the cam-ring above the stems and engaging portions thereof, the posts extending up from the base-plate and the saucer supported by said posts above the chuck-jaws, substantially as described.

In testimony whereof we affix our signatures in presence of two witnesses.

WILLIAM BURKE.

WILLIAM HENRY THOMPSON.
